(57) CLAIM

The design for a heated food holding cabinet, as shown and described.

DESCRIPTION

FIG. 1 is a perspective view of a heated food holding cabinet in accordance with the present invention.

FIG. 2 is a right side elevational view thereof.

FIG. 3 is a left side elevational view thereof.

FIG. 4 is a front view thereof.

FIG. 5 is a rear view thereof.

FIG. 6 is a top plan view thereof; and,

FIG. 7 is a bottom plan view thereof.

The broken line showing of environment in the drawings is included for the purpose of illustrating only and forms no part of the claimed design.
